US00D841913S

(12) **United States Design Patent** (10) **Patent No.:** **US D841,913 S**
Renner et al. (45) **Date of Patent:** **** Feb. 26, 2019**

(54) **CLEANING TOOL**

(71) Applicant: **3M INNOVATIVE PROPERTIES COMPANY**, St. Paul, MN (US)

(72) Inventors: **Megan E. Renner**, St. Paul, MN (US); **Matthew D. Chaffee**, Minneapolis, MN (US); **Mark W. Baldwin**, Woodbury, MN (US); **Michael C. Mooney**, Coon Rapids, MN (US)

(73) Assignee: **3M INNOVATIVE PROPERTIES COMPANY**, St. Paul, MN (US)

(**) Term: **15 Years**

(21) Appl. No.: **29/621,661**

(22) Filed: **Oct. 10, 2017**

(51) LOC (11) Cl. **07-05**

(52) U.S. Cl.

USPC **D32/41**

(57) **CLAIM**

The ornamental design for a cleaning tool, as shown and described.

DESCRIPTION

FIG. 1 is a perspective view showing the new design for a cleaning tool;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The portions of the cleaning tool in FIGS. 1-7 shown in broken lines are included to show features that form no part of the claimed design.

1 Claim, 5 Drawing Sheets
